UNITED STATES PATENT OFFICE.

OSCAR W. MUELLER, OF CINCINNATI, OHIO.

RADIAL DRILL.

SPECIFICATION forming part of Letters Patent No. 737,948, dated September 1, 1903.

Application filed August 11, 1902. Serial No. 119,288. (No model.)

To all whom it may concern:

Be it known that I, OSCAR W. MUELLER, a citizen of the United States, residing at Cincinnati, in the county of Hamilton and State 5 of Ohio, have invented certain new and useful Improvements in Radial Drills, of which the following is a full, clear, and exact description, reference being had to the accompanying drawings, forming part of this specification.

10 The object of my invention is to produce a drill having a non-revolvable column and carrying a radial arm capable of being elevated or lowered and also revolved around said column and supported by a cap-piece suitably 15 journaled on the upper end of said column, and this object I obtain in a manner to be presently described.

In the accompanying drawings, Figure 1 is a side elevation of a radial drill embodying 20 my invention, some of the parts not concerning my present invention being omitted. Fig. 2 is a central sectional elevation of the cap and top of the column, showing the bearing thereon. Fig. 3 is a sectional plan view on 25 the dotted line $\alpha\alpha$ of Fig. 1.

The same letters of reference are used to indicate identical parts in all the figures.

Referring to Fig. 1, A is the base-plate, of the usual or any suitable construction, to 30 which is rigidly secured in any suitable manner the cylindrical column B.

C is the radial arm which carries the drilling mechanism, of the usual or any suitable construction, and which projects at right angles from the column B. It is provided with a split sleeve C', which surrounds and snugly embraces the column B, so that it can be clamped tightly to the column to hold the radial arm C in any of its adjusted positions or 40 can be unclamped therefrom to permit said arm to be swung around the column or to be raised or lowered thereon.

Journalized on the top of the column B is a cap D, provided with a central journal E for the driving-shaft and with such other journal-bearings F G as are necessary in this class of machines. Between the cap D and column B, I place any suitable antifriction-bearing, such as a ball-race d, in the cap D and a similar ball-race b in the top of the column B, with balls c placed between the two ball-races d b to form a ball-bearing, though of course a

roller-bearing or any other antifriction-bearing would accomplish the same result—namely, that of allowing the cap D to revolve 55 on the top of the column B with the least possible amount of friction.

Journalized in the cap D, as at F, is a lead-screw H, which passes through a nut I on the radial arm C and serves to raise or lower the 60 arm C by the revolution to right or left of the lead-screw H. This lead-screw H carries the weight of the radial arm C, except as will be now described. When the radial arm C is adjusted to the desired position for drilling, it 65 is rigidly locked to the column B by hand lock-levers J, working on screw-studs j, passed through lugs e on opposite sides of the opening f in the split sleeve C' of the radial arm C, as clearly shown in Fig. 3. This construction constitutes a convenient and efficient lock; but any other suitable lock may be employed to accomplish the same purpose. The lead-screw H may be geared, as shown in Fig. 70 1, to the driving-gear K of the machine, but 75 may be driven by hand or in any other suitable manner without departing from the spirit of my invention.

The drill-driving shafts L M and their connecting-gearing N O are of the usual construction and as they do not concern this invention need no further description.

P is any suitable cone belt-pulley for transmitting power from any source to the driving-gear K through the medium of the vertical 85 shaft Q, Fig. 3, passing through the central aperture in the column B and connecting through beveled gearing with the driving-pulley P. The great desideratum in radial drills is to secure rigidity of the arm C, and 90 this I accomplish by journaling the arm C on the cylindrical rigid column B, rigidly secured to the base-plate A.

It is obvious from the above description that I produce a radial drill which is rigid in 95 operation, simple and easy of manipulation, and cheap in construction, for the reason that I use a rigid column and avoid the necessity of journaling the column itself.

Having thus fully described my invention, 100 I claim—

1. In a radial drill, the combination of a base-plate, a cylindrical column rigidly secured thereto, an angularly-adjustable arm

directly journaled on said column, means for suspending said arm from the top of said column, means for raising or lowering said arm on said column, and means for clamping said arm around said column, substantially as described.

2. In a radial drill, the combination of a base-plate, a cylindrical column rigidly secured thereto, an angularly-adjustable arm 10 journaled on said column, a cap journaled on the top of said column, means for suspending said arm from said cap, means for raising or lowering said arm on said column, and means for clamping said arm to said column, substantially 15 as described.

3. In a radial drill, the combination of a base-plate, a cylindrical column rigidly secured thereto, an angularly-adjustable arm journaled on said column, a cap journaled on 20 the top of said column, antifriction-bearings interposed between said cap and said column, means for suspending said radial arm from said cap, means for raising or lowering said arm on said column, and means for clamping 25 said arm to said column, substantially as described.

4. In a radial drill, the combination of a base-plate, a cylindrical column rigidly secured thereto, an angularly-adjustable arm journaled on said column, a cap journaled on 30 the top of said column, a lead-screw journaled in said arm and cap for the purpose of suspending and raising or lowering said arm, and means for locking said arm in any adjusted position on said column, substantially 35 as described.

5. In a radial drill, the combination of a base-plate, a cylindrical column rigidly secured thereto, an angularly-adjustable arm journaled on said column, a cap journaled on 40 the top of said column, antifriction-bearings interposed between said cap and said column, a lead-screw journaled in said cap and said arm for the purpose of suspending and raising or lowering said arm, and means for locking 45 said arm in any adjusted position on said column, substantially as described.

OSCAR W. MUELLER.
